UNITED STATES PATENT OFFICE.

GEORGE F. POTTLE, OF BOSTON, ASSIGNOR OF TWO-THIRDS TO WARREN S. HILL, OF HYDE PARK, AND ROYAL O. STORRS, OF DEDHAM, MASS.

WRENCH.

SPECIFICATION forming part of Letters Patent No. 317,670, dated May 12, 1885.

Application filed November 28, 1883. (No model.)

To all whom it may concern:

Be it known that I, GEORGE FRANK POTTLE, of Boston, in the county of Suffolk and State of Massachusetts, have invented certain new 5 and useful Improvements in Wrenches, of which the following is a specification.

My invention relates to that class of wrenches which are called "self-gripping" wrenches, and has for its object to make the wrench 10 more automatic in its action and of increased strength and durability. These objects I attain by the mechanism illustrated in the accompanying drawings, in which—

Figure 1 shows my invention in elevation. 15 Fig. 2 shows the same in section. Fig. 3 shows in detail a spiral spring and a protecting-thimble.

The shank A A' and the fixed jaw B, together with the handle C of my wrench, are 20 made in the usual manner. The screw-nut D works on the shank A', as shown, and is provided with a groove, K, near one end, into which fits a projection, H, of the housing E. The movable jaw M is connected to the housing E by the pivot V, Figs. 1 and 2, so that 25 it may swing down and toward the jaw B as the strain is applied to it.

S, Fig. 2, is a spring placed within and under the jaw M, and serves to throw it up.

L is a projection from the movable jaw M, 30 which is intended to come in contact with the pipe or rod to be turned, and to cause the said jaw M to swing upward, as indicated by the arrow G, and thus automatically grip the interposed pipe or rod.

L' is a recess made in the fixed jaw for the purpose of allowing the movable jaw M to be moved up into close contact with the said fixed jaw B.

T is a thimble partially inclosing the spring 40 S, its object being to protect the spring from dirt, dust, &c., and also to secure its more perfect action.

I claim—

The movable jaw M, provided with the projection L, in combination with the pivot V, the housing E, and adjusting-screw D, all arranged and constructed substantially as described, and for the purpose set forth.

GEORGE F. POTTLE.
